DAVID A. REED, OF BERKELEY, CALIFORNIA

ARCH SUPPORT AND CALLOUS RELIEVING PAD

Application filed May 3, 1930. Serial No. 449,446.

The invention is for an arch support and callous relieving pad, and has particular reference to a pad adapted to be worn in the shoe for relief of callouses in the vicinity of the metatarsal arch.

The invention contemplates the provision in a shoe of a pad particularly adapted and placed to effectively relieve callouses, bunions and corns on the sole of the foot or on the bottom of the toes, fastening means being provided and positioned in the shoe to suit each individual case.

The invention is clearly illustrated in the accompanying drawings in which:

Fig. 1 is a bottom plan view of a human foot and my invention in position to relieve a callous adjacent the metatarsal arch;

Fig. 2 is a longitudinal section through the pad, and indicating its relative position to the third metatarsal bone.

The pad consists of a section of wool felt or other resilient material compressed or skived to the contour 3 indicated in Fig. 2 of substantially ogee form, providing a very thin peripheral edge 4 and a flat undersurface 5, the periphery being of substantially triangular conformation with convex sides 6 and 7, concave base 8 and rounded vertices 9.

A snap fastener 10 is provided with the male member attached to the pad, the female member being imbedded in the sole 12 of the shoe so as not to interfere with the foot of the wearer when the pad is removed.

The pad is so positioned in the shoe as to relieve the pressure on the callous, corn or bunion, the female section of the snap fastener being imbedded in the sole of the shoe in such position as to retain the pad in the position outlined above. The pad may then be inserted and removed at will and the snap fastener member in the shoe, being flush with the inner surface of the sole will cause no inconvenience to the foot.

The exact form of the pad is such that the edge 7 and surface 11 are adapted to conform to the metatarsal arch and by supporting this arch in normal position, the cause is removed and the callous relieved. The edges 6 and 8 are adapted to conform to the approximate contour of the fifth and first meta-

tarsal bones extending backward adjacent to the internal cuneiform bone. By this arrangement, the entire arch is supported in a normal and comfortable position.

What I claim is:

A callous relieving pad consisting of a formed or skived felt or other resilient pad with a substantially flat undersurface provided with the male member of a snap fastener attached therein adjacent the rearward vertex and adapted to cooperate with the female member thereof imbedded in the inner sole of a shoe, said pad having a substantially thick central portion of segmental spheroidal conformation continuing into reverse arcuate conformation to a thin peripheral edge, the peripheral contour of said pad approximating a triangle with convex base and one convex side and one concave side, said convex base and segmental spheroidal section conforming to the metatarsal arch, said convex side conforming to the fifth metatarsal bone and the concave side conforming to the first metatarsal bone to properly support the entire metatarsal section of the foot.

In testimony whereof I have affixed my signature.

DAVID A. REED.
